US00D578017S

(12) **United States Design Patent**
Friedland et al.

(10) **Patent No.:** **US D578,017 S**
(45) **Date of Patent:** **** Oct. 7, 2008**

(54) **SIDE TEAR SHAPED VACUUM POUCH**

(75) Inventors: **Jason Friedland**, Franklin, TN (US); **Angel Hernandez**, Nolensville, TN (US); **Rebecca Morgan Valentine**, Franklin, TN (US); **Peter Slusarczyk**, Nolensville, TN (US)

(73) Assignee: **MARS, Incorporated**, McLean, VA (US)

(**) Term: **14 Years**

(21) Appl. No.: **29/287,536**

(22) Filed: **Aug. 17, 2007**

(51) **LOC (8) Cl.** **09-05**

(52) **U.S. Cl.** **D9/707**

(58) **Field of Classification Search** D9/703-710, D9/713-714, 720-722, 430-432, 414, 418, D9/424; 383/103, 107, 113, 114, 45, 47, 383/200, 203, 100, 108; 229/87.06, 200; 426/106

(57) **CLAIM**

The ornamental design for a side tear shaped vacuum pouch, as shown and described.

DESCRIPTION

FIG. 1 is a perspective view of a side tear shaped vacuum pouch showing our new design;

FIG. 2 is a top view of the design shown in FIG. 1, wherein the bottom view is identical or a mirror image thereof;

FIG. 3 is a front view of the design shown in FIG. 1;

FIG. 4 is a rear view of the design shown in FIG. 1; and,

FIG. 5 is a right side view of the design shown in FIG. 1, wherein the left side view is identical or a mirror image thereof.

The broken lines shown in the drawings are for illustrative purposes and form no part of the claimed design.
